EARTH SCRAPING, TRANSPORTING,
SPREADING, AND LEVELING APPA-
RATUS

Carroll L. Evans, Tipton, Calif.

Application June 28, 1948, Serial No. 35,654

3 Claims. (Cl. 37—129)

1

The present invention relates to improvements in an earth scraping, transporting, spreading and levelling apparatus. It consists of the combinations, constructions and arrangement of parts, as hereinafter described and claimed.

An object of my invention is to provide an apparatus having a wide range of use for digging or scraping material, transporting the material as the apparatus is advanced, discharging the material and spreading the latter to desired depths, all of these operations being under direct control of the operator. The apparatus is designed to be towed by a suitable draft vehicle, such as a tractor. A single controller is provided on the draft vehicle within easy reach of the operator, and the various functions of the apparatus can be performed with rapidity and ease to meet the requirements.

Other objects and advantages will appear as the specification proceeds, and the novel features of my invention will be particularly set forth in the claims hereunto appended.

For a better understanding of the invention, reference should be had to the accompanying drawings, forming part of this application, in which:

Figure 1 is a side elevation of my apparatus illustrated in scraping or digging position;

Figures 2 and 3 are rear and front views thereof, respectively;

Figure 4 is a top plan view;

Figure 5 is a side elevation of my apparatus disclosed in transporting position;

Figure 6 is a side elevation with parts in section showing the apparatus in spreading and levelling position;

Figure 7 is a transverse vertical sectional view taken along the line VII—VII of Figure 5;

Figures 8 and 9 are oblique views of the bucket and gate, respectively, that I employ;

Figure 10 is a side elevation of a modified form of the bucket-operating link; and

Figure 11 is a side elevation illustrating a modification of the gate-operating link.

While I have shown only the preferred forms of my invention, it should be understood that various changes, or modifications, may be made within the scope of the annexed claims without departing from the spirit thereof.

In carrying my invention into practice, I provide a chassis indicated generally at A, which is adapted to be towed by a suitable draft vehicle, such as a tractor B. Broadly speaking, this chassis has a bucket C and a gate D supported thereon, both of which are operated by a hydraulic ram E. The latter is actuated by a hy-

2

draulic pump F mounted on the tractor, the valve controller 10 of the pump being within easy reach of the tractor operator. Conduits 11 and 12 extend from this pump, and are alternately employed as pressure and return lines.

The conduits 11 and 12 communicate with opposite ends of a cylinder 14, forming part of the hydraulic ram. When fluid is delivered through the conduit 11 to the rear portion of the cylinder, 10 a piston rod 15 of the ram is extended outwardly relative to the cylinder. At the same time, fluid is returned from the forward portion of the cylinder through the conduit 12 and back to the pump F. On the other hand, when fluid is delivered from the pump to the forward portion of the cylinder 14 by way of the conduit 12, the piston rod 15 will be retracted, and fluid will be exhausted from the rear portion of the cylinder 14 and returned over the line 11 to the hydraulic pump. The valve controller 10 and the pump F are conventional in design and their operations are well understood in the art to which they pertain.

Referring now to the chassis A in more detail, 25 it will be noted a substantially rectangular-shaped main frame is provided, which includes side members 16 that are interconnected by transverse beams 17 and a draft tongue 17a. The latter is fashioned with an eye 18, which may be 30 coupled to a draw-bar 19 on the tractor by a pintle pin 20. Thus the draw-bar of the tractor constitutes the support for the forward end of the chassis.

In order to support the rear end of the chassis A, I make use of a pair of ground-engaging wheels 21. Brackets 22 are anchored to the rearmost cross beam 17 (see Figures 1 and 4-6) and carry an axle 23 on which the wheels are mounted.

The gate D includes a front plate 24 extending 40 transversely between the side members 16 of the chassis and side panels 25. The latter extend rearwardly from the front plate 24 and are provided with trunnions 26, which are journaled in bearings 27 mounted on the side members 16. 45 The gate is swingable into various angular positions about the horizontal axes of the trunnions 26 by means and for the purpose hereinafter set forth.

The bucket C is defined by parallel side walls 50 28, a rear wall 29, and a bottom plate 30. The front 31 of the bucket is open, except when the gate D is lowered to form a closure thereover (see Figure 5). The side panels 25 of the gate are pivotally connected by bolts 32 to the side walls 55 28 of the bucket. Thus the gate forms a support for the bucket. It will be noted that the for-

ward portion of the bottom plate 30 is fashioned with a sharpened edge 33. This edge is adapted for cutting or digging into the ground 34 when the bucket is lowered into the position shown in Figure 1 and the chassis A is advanced.

The forward part of the chassis is provided with bearings 35 in which a main shaft 36 is journaled. This shaft has a crank arm 37 fixed thereto so as to rotate the shaft. The piston rod 115 of the hydraulic ram E is pivotally connected to the crank arm 37 by means of a pin 38. The rear part of the cylinder 14 of the ram is pivotally connected by a bolt 39 to a bracket 40 fixed to and rising from one of the cross beams 17 (see Figure 6).

The opposing ends of the main shaft 36 have a pair of bell-cranks G fixed thereto. The short arms 41 of these bell-cranks are pivotally connected by bolts 42 to gate-operating links H at the forward ends of the latter. The rear ends of these links are pivotally secured by stud 43 to the side panels 25 of the gate D. The long arms 44 of the bell-cranks G are pivotally connected by bolts 45 to the forward ends of bucket-operating links J. The rear ends of the latter links are pivotally connected by studs 46 to the side walls of the bucket C.

Figure 10 discloses a modified form of a bucket-operating link J', which may be used in place of the links J previously described. These modified links are provided with turnbuckles 47 of conventional design in order to allow adjustment of the overall length of the links. Likewise, Figure 11 illustrates a modification of a gate-operating link H'. It will be understood that the latter may be substituted for the links H hereinbefore described. The links H' are provided with turnbuckles 48 for the purpose of permitting the overall length of these links to be adjusted.

Having thus described the various parts of my apparatus the operation and use thereof are briefly described as follows:

Assuming that the chassis A is coupled to the drawbar 19 of the tractor B, and the valve controller 10 occupies the "digging" position indicated in Figure 1, it will be observed that the bucket C has its cutting edge 33 disposed below the surface 34 and the gate D occupies a raised position to uncover the open front 31 of the bucket. As the apparatus is advanced, a load of material 34a will be guided into the bucket. The cutting edge 33 can be adjusted to serve as a ground leveller, if desired.

After a load of dirt has been picked up by the bucket, the operator can shift the valve controller to the "carrying" position (see Figure 1). This will allow the hydraulic pump F to deliver fluid over the conduit 11 to the rear portion of the cylinder 14. A corresponding withdrawal of fluid will be accomplished from the forward portion of the cylinder 14, which will be returned by the conduit 12 to the hydraulic pump. As a result, the piston rod 15 will be extended relative to the cylinder 14 until it occupies the position disclosed in Figure 5.

This extension of the piston rod 15 will swing the crank arm 37 and bell-cranks G in a clockwise direction, resulting in pulling the gate-operating links H and the bucket-operating links J forwardly until they reach the positions shown in Figure 5. This forward movement of the links H swings the gate D about its trunnions 26 until the gate forms a closure over the open front 31 of the bucket so as to retain the load of material 34a in the bucket. Meanwhile the forward

5 pull on the links J causes the bucket C to swing about the bolts 32, which are arranged between the side panels 25 of the gate and the side walls 28 of the bucket. At this time, the apparatus is in transporting position, and the load can be transferred to the location where it is to be dumped or spread.

When the operator on the tractor desires to dump the load of material, the valve controller is moved into the "dumping" position shown in Figure 1. This will allow the pump F to discharge more fluid through the conduit 11 to the rear portion of the cylinder 14 and withdraw a corresponding amount of fluid through the conduit 12 from the front portion of the cylinder 14. This causes a further extension of the piston rod 15 (see Figure 6), resulting in moving the bucket C toward vertical position so as to discharge the load of material 34a therefrom. The edge 33 of the bucket may be employed for leveling the discharge load, or used for scraping the ground to level the latter.

After the load of material has been discharged, the operator may return the valve controller 10 to "carrying" position or to "digging" position, depending upon the work to be accomplished.

It should be noted that the links H constitute positive means for swinging the gate D about its trunnions 26; also, the links J provide positive means for moving the bucket C about the pivotal bolts 32 arranged between the gate and bucket. The provision of the links H and J in pairs insures swinging of the gate and bucket without binding or creating twisting strains on the gate and bucket. The single valve controller unit F is arranged on the tractor B so as to be actuated under direct control of the operator.

I claim:

1. In an earth scraping, transporting, spreading and levelling apparatus: a chassis frame; a gate journaled on said frame for swinging about a horizontal axis; the gate including a front plate extending transversely relative to said frame and side panels extending rearwardly of the gate journals; a bucket anchored to and pivotally supported by the side panels on a horizontal axis disposed rearwardly with respect to the gate journals; the bucket having an open front provided with a cutting edge; the gate being swingable on its journals into lowered position in which it forms a closure over the open front of the bucket, during which movement the pivotal anchorage between the side panels and the bucket positively operates to elevate the forward end of the bucket; the gate also being swingable into raised position on its journals to uncover the front of the bucket, during which movement the pivotal anchorage between the side panels and bucket positively operates to lower the forward end of the bucket; a main shaft journaled on the chassis frame; means for turning the shaft in either direction about its axis; a bell-crank fixed to said shaft and movable therewith; a gate-operating link pivotally connected above the main shaft to one arm of the bell-crank and to the gate above the gate journals for positively raising and lowering the gate relative to the bucket when said shaft is turned in the desired direction; and a bucket-operating link pivotally connected to the other arm 40 of the bell-crank and to the bucket at a point rearwardly of the pivotal anchorage between the side panels and the bucket for positively raising and lowering the bucket when said shaft is turned in the desired direction.

2. In an earth scraping, transporting, spread-

ing and levelling apparatus; a chassis frame; a gate journalled on said frame for swinging about a horizontal axis; the gate including a front plate extending transversely relative to said frame and side panels extending rearwardly of the gate journals; a bucket anchored to and pivotally supported by the side panels on a horizontal axis disposed rearwardly with respect to the gate journals; the bucket having an open front provided with a cutting edge; the gate being swingable on its journals into lowered position in which it forms a closure over the open front of the bucket, during which movement the pivotal anchorage between the side panels and the bucket positively operates to elevate the forward end of the bucket; the gate also being swingable into raised position on its journals to uncover the front of the bucket, during which movement the pivotal anchorage between the side panels and bucket positively operates to lower the forward end of the bucket; a main shaft journalled on the chassis frame; means for turning the shaft in either direction about its axis; a pair of bell-cranks fixed to said shaft and movable therewith; a pair of gate-operating links pivotally connected above the main shaft to the bell-cranks and to said side panels above the gate journals on opposite sides of the gate for positively raising and lowering the gate relative to the bucket when said shaft is turned in the desired direction; and a pair of bucket-operating links pivotally connected to the bell-cranks and to opposite sides of the bucket at points rearwardly of the pivotal anchorage between the side panels and the bucket for positively raising and lowering the bucket when said shaft is turned in the desired direction.

3. In an earth scraping, transporting, spreading and levelling apparatus; a chassis frame; a gate journalled on said frame for swinging about a horizontal axis; the gate including a front plate extending transversely relative to said frame and

side panels extending rearwardly of the gate journals; a bucket anchored to and pivotally supported by the side panels on a horizontal axis disposed rearwardly with respect to the gate journals; the bucket having an open front provided with a cutting edge; the gate being swingable on its journals into lowered position in which it forms a closure over the open front of the bucket, during which movement the pivotal anchorage between the side panels and the bucket positively operates to elevate the forward end of the bucket; the gate also being swingable into raised position on its journals to uncover the front of the bucket, during which movement the pivotal anchorage between the side panels and bucket positively operates to lower the forward end of the bucket; a main shaft journalled on the chassis frame; means for turning the shaft in either direction; gate-operating means pivotally connected to the gate panels at a point above the gate journals and operated by said shaft for positively raising and lowering the gate relative to the bucket when said shaft is turned in the desired direction; and bucket-operating means connected to the bucket at a point rearwardly of the pivotal connection between the gate-operating means and the gate, and also operated by said shaft for positively raising and lowering the bucket when said shaft is turned in the desired direction.
